UNITED STATES PATENT OFFICE.

WALDO J. GUILD, OF WORCESTER, MASSACHUSETTS, AND LEWIS CLIFFORD KENYON, OF NEW YORK, N. Y., ASSIGNEES TO THE HEALD MACHINE COMPANY, OF WORCESTER, MASSACHUSETTS, A CORPORATION OF MASSACHUSETTS.

GRINDING MACHINE.

Application filed January 7, 1926, Serial No. 79,849. Renewed April 3, 1928.

The invention relates to grinding machines, particularly those adapted to grind the internal peripheral surfaces of sleeves, gears, bushings, and like articles, and is an improvement upon and an addition to the prior invention shown and claimed in the copending application of Kempton and Gallimore, Serial No. 6,689, filed February 4, 1925, and also to the prior invention shown and claimed 10 in the copending application of Heald, Guild, Burns and Garno, Serial No. 4,466, filed January 24, 1925.

In particular, the invention provides means for automatically dressing the rapidly rotating grinding wheel a plurality of times during the grinding of a workpiece, said dressing being initiated by devices responsive to the movement of a gauging or caliper device that is maintained in operative 15 relation to the surface being ground. Between the said dressing operations the grinding wheel is brought into contact with the work, to make at the least a single cutting traverse on the surface thereof. By thus interrupting the grinding operation two or 20 more times to dress and true the grinding wheel, the latter is kept sharp and "free cutting," in consequence of which the relative advance or cross feed between the wheel and the workpiece occurs without producing any 25 spring in the grinding wheel spindle, once the first dressing operation has occurred.

Other and further objects of the invention will appear from the following detailed 30 description, taken in connection with the accompanying drawings, in which—

Fig. 1 is a front elevation of a grinding machine built in accordance with the invention, showing the carriage in the work 35 re-moving position.

Fig. 2 is a plan view of the work caliper mechanism.

Fig. 3 is a front elevation showing the switch operating mechanism on an enlarged 40 scale.

Fig. 4 is a section on the line 4—4 of Fig. 3.

Fig. 5 is a sectional view on the line 5—5 of Fig. 4, showing the switch, together with a wiring diagram of the machine.

Figs. 6, 7, 8 and 9 are views on a reduced

scale of the switch mechanism of Fig. 3, showing the parts in different positions.

Fig. 10 is a plan view of the machine, showing the carriage fully withdrawn, as in Fig. 1.

Fig. 11 is a front elevation, showing the parts in the normal grinding position.

Fig. 12 is a fragmentary view from the rear of the machine, showing the dresser moving mechanism.

Fig. 13 is a sectional view on the line 13—13 of Fig. 12.

Like reference characters refer to like parts throughout the drawings.

Referring first to Fig. 1, the machine provides the usual reciprocating table or carriage 1 which is ordinarily provided in any internal grinding machine. In such a machine, either the grinding wheel or the work to be ground may be carried on the table 1, the reciprocation of the latter being utilized in either case to produce a relative traversing movement between the grinding wheel and the work. As here shown, the table 1 supports and carries a wheel head 2, while the work which is to be operated upon is held in a work head 3, the latter being carried by a bridge 4, which spans the slideways provided by the machine frame for the back and forth movement of the table 1.

This back and forth movement of the table 1 to cause the rotating grinding wheel 5 to make the required interior traverse of the rotating workpiece 6 may be imparted in any well known manner, as for instance, by the use of the fluid pressure controlling and reversing mechanism which forms the subject matter of the copending application of Heald and Guild, Serial No. 629,882, filed April 4, 1923, now Patent No. 1,582,468, granted April 27, 1926.

Such mechanism, or its equivalent, forms no part of the present invention, and a detailed description thereof is therefore unnecessary; it is sufficient to note for the purposes of the present application, that the driving means employed for the reciprocation of the table 1, be it hydraulic drive, or gear drive, or any other type, procures the reversal of said table at each end of the latter's normal working stroke by the use of spaced ad-

justable dogs 7 and 8, carried by the table 1 and adapted to alternately engage and move a reversing member 9; the latter, during the grinding operation, when the wheel 5 is moving back and forth within the workpiece 6, is situated between the two dogs 7 and 8 in position to be struck alternately by said dogs, and by its consequent movement, first in one way and then the other, effects the reversals 10 in the travel of table 1. In the machine here- in illustrated, the grinding wheel 5 is rotated at high speed in any suitable manner, as for instance, by a belt drive for the wheel spindle 10, the latter for this purpose carrying a pul- 15 ley 10^a. The workpiece 6 is also rotated, but at a slower speed, this rotation being imparted in any suitable manner as by a belt drive, not shown, from a countershaft.

Referring to Figs. 1 and 10, the machine 20 also embodies the usual instrumentalities for both manual and automatic cross feed between work and wheel, here shown as embodied in a screw shaft 11 for feeding the wheel head 2 transversely of the table 1. Said screw shaft 11 may be operated, if desired, by the usual hand wheel 11^a. The automatic operation of said screw shaft 11 is effected in the usual manner, at each reciprocation of the table 1, by a fixed dog or stop 25 12 which is engaged by a roller 13 on a pivoted arm 14; the movements of said arm are transmitted through a pawl 14^a and ratchet wheel 14^b and reduction gearing, not shown, to the screw shaft 11, thereby to obtain the 30 automatic cross feed of the grinding wheel 5 at each reciprocation of the table.

As shown in Fig. 2, a member 15 has at one end a work caliper point 16 adapted, during the operation of grinding a work- 40 piece, to bear against the internal surface which is being ground, and to maintain its contact with said surface as the hole in the workpiece is gradually enlarged by the grinding action of the wheel. The member 45 15 is to all intents and purposes a lever, said member, for the movement required of it to maintain the point 16 in constant contact with the interior of the gradually enlarging hole in the workpiece, being sup- 50 ported by a pair of flexible U-shaped flat springs 17 and 18, which springs cross each other, and are attached to two adjacent sides of a rectangular block portion 19 of member 15. At their other ends the crossed springs 55 17 and 18 are attached to two inner surfaces 20 and 21 of the box 22, these surfaces 20 and 21 being at right angles to each other, and the box 22 providing an opening 23 of sufficient size to permit the inward extension 15^a, 60 of member 15, to move freely about the pivotal axis which is afforded by the intersection of the planes of the U-shaped springs 17 and 18. This pivotal movement is accom- 65 plished by the flexing of these two springs, and takes place in the entire absence of lost

motion since there is no bearing or pivot pin. Consequently, any movement of the exten- 70 sion 15^a of member 15 within the box 22, is invariably in exact accordance with the movement of caliper point 16 in maintaining contact with the surface of the gradually enlarging hole in the workpiece.

Such motion of the member 15 is adapted to be transmitted to an indicator lever 24, pivoted at 25 within the box 22, with its free end adapted to move across the graduations 75 of a suitable scale 26. Lost motion may be eliminated at bearing 25 by a spring 25^a. The connection between extension 15^a and indicator lever 24 is made by a spring 80 27, which draws the parts together and maintains the lever 24 in contact with the end of a screw 28, said screw being adjustably threaded in extension 15^a and passing at its head end through a suitably 85 enlarged slot or hole 29 in box 22, so as to permit adjustment from the exterior of said box. Fig. 2, representing an illustrative em- 90 bodiment of this mechanism, shows the end of screw 28 in a cut out portion made in lever 24, but it must be understood that said screw and lever are entirely unconnected, and merely bear against each other by reason of the pressure of spring 27. By turning the screw 28, the indicator lever 24 can be made to assume any desired position relative to the member 15, and said screw 28 is main- 95 tained in any given setting, and displacement thereof prevented by any suitable friction device, such as a spring 30. With the ar- 100 rangement above described, a very slight movement of the caliper point 16 is multiplied many times in being transmitted to the indicator lever 24, as will be readily under- 105 stood.

In the operation of the mechanism, the caliper point 16 maintains contact with the work, the movement of member 15 for this purpose being obtained by the pressure of a spring 31, and such movement, greatly manipulated, being transmitted through the above described connections to the indicator lever 24.

The multiplied movement of the latter is made use of at predetermined points in the 115 grinding of each workpiece to set in operation the wheel dressing instrumentalities a plurality of times, and finally to bring about a cessation of the grinding and cause the grinding wheel 5 to withdraw from the work- 120 piece 6. To this end the lever 24 carries three or more contacts, in this embodiment shown as three, namely a contact 32 to bring about the first stage dressing, a contact 33 to cause the dressing instrumentalities to again come 125 into operation, which we call the second stage dressing, and a contact 34 to bring about the cessation of grinding. In the paths of these three contacts 32, 33 and 34, the box 22 pro- 130 vides suitable insulated stationary terminal

contacts 35, 36 and 37, respectively. In the movement of lever 24, the points 32 and 35 come first into contact, then points 33 and 36, and finally points 34 and 37, and in order to permit this succession of contacts, points 32 and 33 are carried at the end of flat springs 38 and 39 respectively, both attached to the lever 24, so that by the yielding of these springs, the subsequent movement of said lever to bring the point 34 into contact with point 37 can take place with a negligible resistance.

As clearly described in the application of Heald, Guild, Burns and Garno, the box 22 is mounted for swinging movement about a pivot 40, and when the final withdrawal movement of table 1 takes place, withdrawing the wheel 5 from the workpiece 6, a cam member 41 strikes a roller 41^a on an arm 41^b attached to the box 22 and swings the box 22, carrying the caliper lever 15, away from the workpiece. A spring 42, see Fig. 1, automatically returns the box 22 to its operative position as the wheel 5 enters a subsequent workpiece 6, and means is provided to allow the caliper point 16, generally a diamond, to enter the new workpiece without striking the mouth of the latter and chipping the point 16. It is not believed necessary to describe these mechanisms and the various adjustments in detail, as they have nothing to do with the present invention, and enough of the caliper mechanism has been described to illustrate said present invention.

Referring now to Fig. 5, the instrumentalities of the present invention, whereby a plurality of wheel dressing operations may be automatically inaugurated, will now be described. The character G indicates a generator of any desired sort, preferably supplying direct current. One terminal of the said generator is grounded and the other terminal is connected by means of a branching lead 43 to the coils of two electromagnets 44 and 45. The other end of the coil of electromagnet 44 is connected by a lead 46 to a stationary contact plate 47 of a switch, generally designated by the numeral 48. The other end of the coil of electromagnet 45 is connected by a lead 49 to the stationary terminal 37. The stationary terminals 35 and 36 are connected respectively by leads 50 and 51 to stationary plates 52 and 53, also part of said switch 48.

The magnet 44 controls, by mechanism to be described, the dressing operation and whenever it is energized, the wheel 5 is dressed by causing it to pass by a diamond 54, see Fig. 1. The magnet 45, when energized, brings about a cessation of the grinding, and prepares the machine for the introduction of a new workpiece.

Referring particularly to Figs. 3, 4 and 5, the switch 48 provides a movable bridge contact member 55, the position of which, as here-

inafter pointed out in connection with said figures and also Figs. 6, 7, 8, and 9, determines which of several electric circuits will be energized. Said bridge contact member 55 is carried by an insulating collar 56. The latter is fastened to a member 57, which in turn is fastened to a central shaft 58 of the switch. Shaft 58 supports the movable parts of the switch, and is itself journalled in a sleeve casting 59 of the switch housing. The member 57 provides a ratchet segment 57^a, by means of which the bridge contact 55 is moved into different positions. The shaft 58 likewise serves as a pivot for a lever 60, the latter carrying a spring pressed pawl 61. Attached to the lever 60 is a connector 62, and when this connector is raised, the pawl 61 actuates the ratchet segment 57^a and thus turns the shaft 58 and associated parts. A hold pawl 63, engaging the ratchet segment 57^a, normally prevents retrograde movement of the shaft 58, said pawl 63 being carried by a lever 64 pivoted at 65. A connector 66 is attached to the other end of this lever 64, and when it is moved downwardly, the pawl 63 is raised, whereupon a coil spring 67, which has been wound up by movement of the shaft 58, acts to return the parts to original position, as shown in Fig. 3. As the outer peripheral radius of the member 57 is greater than the radial distance of the segment 57^a, the parts will be stopped as shown in Fig. 9, notwithstanding pawl 63 is raised. A spring 68 tends to hold the pawl 63 in engagement with the ratchet segment 57^a. Before proceeding with a description of the operation of these parts, the machine motions inaugurated by energization of the magnets 44 and 45, will be described.

Energization of the electromagnet 44 causes attraction of an armature member 69, and the consequent elevation of its attached lever arm 70, these parts being pivoted at 71 on the front of the machine. See Fig. 1. Such movement of the lever arm 70, responsive to the engagement of contacts 32 and 35, or 33 and 36, is made use of to automatically interrupt the grinding operation on the workpiece 6 for the dressing and truing of the grinding wheel 5. This involves the withdrawal of the grinding wheel 5 from the workpiece, and the disposal, in the temporarily amplified path of movement of said wheel, of the dressing device or diamond 54; these two operations are effected through the medium of the lever arm 70 in the following manner.

As fully described in the copending application of Heald and Guild, Serial No. 25,900, filed April 25, 1925, the dressing device 54 may be moved into operative position through the medium of fluid under pressure, more especially when such pressure fluid is employed for imparting reciprocation to the table 1. The means by which said pressure fluid is

made available for the movement of dressing device 54 into operative position forms, of itself, no part of the present invention, being fully described and claimed in the aforesaid 6 application of Heald and Guild, Serial No. 25,900; it is sufficient to note, for purposes of this application, that, as described in said Heald and Guild application, the dresser point 54, suitably mounted on an adjustable 10 screw plug 72, is lowered into operative position by the downward swinging movement of a carrying member 73, which turns on a trunnion 74 provided by a suitable standard 15 75 rising from the stationary frame of the machine. When the lever arm 70 is moved, a downward extension 76 thereof communicates said movement to a valve 77, Fig. 1, thus making the pressure fluid active, through piping 110 (see Figs. 12 and 13), 20 against a piston 111, which is operatively associated with the member 73, thereby to swing the dresser point 54 from the inoperative position, that it normally occupies, down into its operative position in the path of 25 grinding wheel 5.

Referring to Figs. 12 and 13, a cylinder 112 is provided at the rear of the machine, the piston 111 being located therein. The piping 110 leads from the valve 77 to the 30 front end of said cylinder. A lever 113, pivoted at 114, has a pin 113^a which normally just touches the rear end of the piston 111. When the latter, by fluid pressure actuation, is moved, the lever 113 is rocked clockwise to 35 the dotted line position of Fig. 13—this action draws backwardly a link rod 115 to which the lever 113 is connected. The link rod is pivotally connected to the carrying member 73, and hence the action described 40 lowers the diamond 54. A handle 78 is also provided for rocking the dresser manually. Our invention, of course, is not limited to the above described use of pressure fluid for disposing the dresser 54 in operative position; 45 obviously, any other type of dresser moving mechanism, such as that disclosed in the said copending application of Heald, Guild, Burns and Garno, Serial No. 4,436, filed January 24, 1925, may be made responsive to the energization of magnet 44.

As before stated, the other operation inaugurated by said engagement is the automatic amplification of the reciprocatory path of table 1, to carry the wheel 5 past the dresser 54. As shown in Fig. 1, the left hand table dog 8, which limits the right hand movement of table 1, is carried by a block 79, which instead of being secured directly to the table 1 as in the case with the block 80 of dog 7, is mounted so as to be capable of sliding freely longitudinally of said table. Under normal conditions, when the table is making its usual working reciprocations to traverse the grinding wheel 5 back and forth 50 within the workpiece, the block 79 of dog 8

is held in definite spaced relation to a block 81, which latter, the same as the block 80 of right hand dog 7, is a stationary block adapted to maintain its predetermined setting or adjustment longitudinally of the table 70 1, as given it by any suitable adjustment of adjusting and holding devices, such for instance, as the hand screw nuts 82, 82 applied to both blocks 80 and 81 and engaging with the screw rack 83 on the table 1. 75

The device employed to hold the slidable block 79 in spaced relation to the fixed block 81 is here shown as a latch lever 84 pivoted at 85 on block 81, and having its free end disposed by gravity in abutting relation to a shoulder 86 on block 79, thereby holding the block 79 at a predetermined distance to the right of block 81. When the latch member 84 is lifted to free its end from the shoulder 86, the normal connection between the slidable block 79 and the fixed block 81 is broken, and when this occurs on the right hand movement of table 1, the dog 8 will bear without effect against the member 9. Thus the right hand movement of the table 90 1 on this particular stroke will be extended beyond the usual reciprocatory working path, and the grinding wheel 5 will be carried out of the hole in the workpiece to a point just beyond that occupied by the dressing device, which latter, as already described, has been moved into operative position as the amplified right hand travel of table 1 begins. 95 This amplified right hand travel of table 1 involves relative sliding movement between 100 said table and the block 79, owing to the obstruction which the reversing member 9 imposes against the dog 8 to prevent the block 79 from moving with the table; finally, the block 79 brings up against the block 81, 105 whereupon the solid backing thus afforded for the block 79 enables the dog 8 to shift the member 9. This procures reversal of the table 1, and the left hand movement of said 110 table thus inaugurated is caused to restore the parts automatically to normal position in the following manner.

A member 87 pivotally mounted on the frame of the machine has a pair of inclined surfaces 88 and 89 for cooperation, respectively, with inclined surfaces 90 and 91 at the lower corners of the block 79. A spring 92 presses said member 87 upwardly. In the normal grinding operation of the machine when the blocks 79 and 81 are connected by latch 84, the surfaces 88 and 89, although in the path of block 79, offer no effective obstruction to the back and forth travel of said block in unison with the table 1, it being obvious that when either lower corner of the block under these conditions strikes either of the bevelled surfaces 90 or 91, such contact will wedge the spring 92 downwardly, said spring yielding sufficiently to allow the block 125 79 to pass over the member 87. However, 130

- when the block 79 has been freed from the block 81 as above described, to amplify a single right hand stroke of the table 1, the ensuing reversal of said table, with the block 79 still free, finds the surface 88 in position to contact with the corner 90 of said block, and under these conditions the obstruction offered is sufficient to overcome whatever friction there may be tending to cause the block 79 to move to the left with the table. The block 79 being thus held stationary while the table 1 and block 81 continue to move to the left, the latch member 84 finally resumes its normal position relative to the block 79, the end of said latch member dropping behind the shoulder 86 and the parts being thus automatically restored to normal position at the conclusion of each single amplified reciprocation of the table 1. Movement of the lever arm 70 is adapted to lift the latch 84, the former having a roller 70^a, which normally lies just underneath said latch.
- The magnet 44 may be seen in dotted lines in Fig. 1, being shown as inclosed in a box like structure 93 on the front of the machine frame. The magnet 45 is located directly behind the magnet 44, and the same pivot 71 that serves to hold the armature 69, lever arm 70 and extension 76, serves also to hold an armature 94 and arm 95 associated with electromagnet 45. As heretofore stated, energization of magnet 45 is adapted to cause final separation of work and wheel, and this is effected in the following manner:—
- Attraction of armature 94 lifts arm 95, interposing the free end of the latter in the path of table dog 8, which dog, as heretofore pointed out, normally on the right hand working stroke of the table, strikes and moves the reversing member 9 to cause a reversal in the direction of table travel. The dog 8 is pivotally mounted at 96 (see Fig. 1) on the carrying block 79 and normally rests by gravity against a pin 96^a. When the arm 95, as above described, moves upwardly into the path of dog 8, the free end of said dog on the right hand movement of the table, engages with and rides upon the upwardly inclined surface of arm 95, and is thus carried clear of reversing member 9. The table 1, therefore, continues its movement to the right, carrying the grinding wheel 5 out of the work and well past the dressing device, being finally brought to a stop by any suitable means, such, for example, as disclosed in the aforesaid copending application of Heald and Guild, Serial No. 629,882, filed April 4, 1923.
- Referring again to Figs. 3 and 4, a shaft 97 is rotatably carried by the box 93 and a lug 98 attached to said box. An actuating arm 99 has a hub 100, which latter is fastened to the shaft 97. The shaft 97 also serves as a pivotal mounting for a second actuating arm 101. Fastened to the front of the shaft 97
- is a lever 102. The connector 62 is pivotally connected to lever 102. The connector 66 is attached to the outer end of actuating arm 101. Attached to the left hand block 81 are a pair of switch operating dogs 103 and 104. The dog 103 is in the path of the arm 99 and adapted to actuate it whenever it is moved past said arm. The dog 104 which, as will be seen from Fig. 3, is somewhat different in shape from the dog 103, is in the path of the actuating arm 101, and is adapted to depress the latter whenever it passes it. In the normal reciprocatory travel of the table to grind a workpiece, neither the arm 101 nor the arm 99 is actuated by the said operating dogs 103 and 104 because in such working position the table 1 does not move out far enough. When the table 1 withdraws to perform the dressing operation by reason of the lifting of the latch 84 as already described, the dog 103 strikes and tilts the arm 99 to a position shown by dotted lines in Fig. 3, as the said table moves outwardly, and again as the said table moves inwardly, this latter time in reverse direction, but to same extent. This double actuation of the arm 99 lifts the connector 62 twice, thereby moving the pawl 61 twice to operate the ratchet segment 57^a.
- When the table 1 is in the position shown in Fig. 1, which is the position it assumes while the operator is taking out the finished workpiece and inserting an unground one, the ratchet segment 57^a, pawl 61 and associated parts, assume the full line position of Figs. 3 and 4, with the bridge 55 as shown in full lines in Fig. 5. The operator having inserted a new unground workpiece 6 in the chuck 6^a of the workhead 3, grasps a lever 105 which is connected, in a manner not necessary to be described herein, to the reversing member 9. The operator shifts said lever 105 to the left, thus moving the reversing member to the right and causing the table 1 to move to the left. The table dog 8, on striking the reversing member 9, is lifted thereover, thus disposing the member 9 between the actuating dogs 7 and 8. Prior to this the dog 103 strikes the arm 99, as shown in Fig. 6, and moves the bridge 55 to the position shown in said figure, thus electrically connecting the stationary contact terminals 52 and 47. The grinding wheel 5 now proceeds to enlarge the internal diameter of the workpiece 6, the table 1 reciprocating back and forth for this purpose. The work caliper box 22, by reason of the fact that cam 41 has been moved from contact with roller 41^a on arm 41^b, has been automatically swung, in response to the force of spring 42, into position to bring the caliper point 16 into contact with the face of the workpiece 6. As the workpiece 6 is enlarged, at a predetermined point determined by the adjusting screw 28, contact is made between the points 32 and 35.
- Referring to Fig. 5, it will be seen that

electrical energy from the generator G now passes along the lead 43 through the electromagnet 44, thence by way of lead 46 to terminal 47 of the switch 48, thence by bridge 55 to terminal 52, thence by lead 50 across the contacts 32 and 35, thence through the machine frame, since the lever 24 is grounded, back to the generator again. This causes attraction of armature 69, and thus the arm 10 is raised, lifting the latch 84, whereupon the table 1 withdraws from the workpiece for a limited distance. At the same time, as already described, the diamond dressing point 54 is lowered into the path of the grinding wheel 5 and the latter is dressed and trued thereby. The grinding wheel 5 then returns to make contact with the workpiece 6 again.

As the table 1 moves outwardly for this dressing operation, the dog 103 again strikes 20 arm 99 and rocks it, bringing the bridge 55 to the position shown in Fig. 7. Immediately thereafter the arm 99 is rocked in the reverse direction and the bridge is brought to the position shown in Fig. 8, where the terminals 47 and 53 are connected. At this time, as the wheel 5 enters the workpiece 6 again, the terminal 32 is still in contact with the terminal 35, but insomuch as the bridge 55 has moved away from the terminal 52, the wheel dressing instrumentalities are not immediately 30 brought into play. Instead, the grinding wheel 5 continues to reduce the workpiece 6, but with a greatly "lessened spark", owing to the fact that the pressure between the two, 35 due to the springing of the spindle 10, has been removed by the dressing and truing operation, which has reduced the wheel in size. When, however, the grinding has proceeded far enough to bring the terminals 33 and 36 40 into contact, the wheel dressing operation is repeated. At this time, the current goes from the generator again by way of electromagnet 44 and lead 46 to stationary terminal 47. Thence, it jumps by means of the bridge 55 45 to the stationary terminal 53, and then, by way of lead 51, across the contacts 33 and 36 to ground again. This causes the machine to go through exactly the same operation as before, and, consequently the bridge 55 is moved 50 again.

It will be noted that we have provided a double motion to the bridge 55 for each amplified movement of the table 1. This is desirable, because when the table reaches its extreme outermost position on the amplified stroke, the current should be shut off from the electromagnet 44, thus allowing the lever 70 to be repositioned, as by means of a cam portion 84 on the latch lever 84. This allows 55 the extension 76 to be returned to normal position, thus moving the valve 77 to neutral and relieving the hydrostatic pressure from the cylinder, not shown, that causes the lowering of the diamond 54. This is desirable in 60 the machine shown, because as fully described 65

in the application of Heald and Guild, Serial No. 25,900 and as illustrated in Figs. 12 and 13, the said diamond 54 is returned to inoperative position by a cam 116 carried by the table 1, a surface 117 of which engages a roller 118 on a forward extension 119 of the lever 113, and it is desirable that this mechanical return movement should be unopposed by pressure in the diamond operating cylinder 112.

The wheel 5 is now back in contact with the workpiece 6 and proceeds to take the final and finishing cuts under no more pressure between wheel and workpiece than is necessary to obtain a cutting for the finish of the workpiece, owing to the double dressing and truing operations. When the workpiece 6 reaches finished size, the contact 34, on the lever 24, engages the stationary contact 37, and at this period, the electromagnet 45 is energized. The current to energize magnet 45 proceeds, by way of lead 43, through said magnet 45 to terminal 37 by way of lead 49, thence to terminal 34 and back to ground. It will be noted that, at this time, it is impossible for the electromagnet 44 to be energized, since the bridge 55 has moved one station beyond the last energizing position, as shown in dotted lines, Fig. 5. Subsequent movements of the pawl 61 after the parts have reached this position avail nothing, since the pawl merely rides up on the circular periphery of the member 57. Upon right hand movement of the table 1, therefore, the dog 8 is lifted by the arm 95 and, consequently, the table proceeds outwardly to the position shown in Fig. 1, where it comes to rest. As the table so moves outwardly, and then only, the dog 104, which is in effect a double cam member, comes into contact with the lever arm 101, depressing the same, thus moving downwardly the connector 66 and raising the pawl 63. At that point the coil spring 67 comes into operation and returns the ratchet segment 57^a, the bridge 55, the shaft 58 and all associated parts to the original position. This is possible because a shield member 106 holds the pawl 61 out of engagement with the segment 57^a till its stroke has been commenced. Figure 9 illustrates the action here, showing the pawl 63 engaged by the end of the segment 57^a.

It will be noted that the contact terminals 35 and 36, which bring the dressing instrumentalities into play, are adjustable in and out, as by means of thumb nuts 107 and 108. Likewise, the position of final withdrawal is adjustable by means of the thumb nut 109, and as already described, the lever 24 as a unit may be adjusted in and out by means of the screw 28. Thus the stage in the reduction of the workpiece at which the first and second dressing, and also the final withdrawal, take place can be readily determined. We have 130

found that it is advantageous to cause the first and second dressing operations to come close together and to set the diamond 54 back of a vertical plane of tangency to the internal 5 surface of the workpiece at the first predetermined dressing position.

The spring of the wheel spindle 10, which is then at its maximum phase, causes the wheel 5 to contact with the diamond 54 and thus be 10 dressed and trued. As aforesaid, the wheel now proceeds to cut the work with greatly diminished "spark," and the second dressing operation will take place practically at that 15 time when the said plane of tangency reaches the diamond. Thus a plural dressing and truing of the wheel 5 is accomplished, with the diamond 54 always reaching the same dressing point, yet the wheel 5 is not excessively reduced, as the spring of the spindle 10 allows 20 enough cuts to be taken between dressing operations so that the contacts 32-35 and 33-36 will not be made simultaneously.

It is obvious that by merely providing an 25 additional pair of contacts in the box 22, an additional stationary terminal in the switch 48 and some more teeth in the segment 57², we could provide for a triple dressing operation, and in fact, any number of operations, but beyond a certain number, such would only 30 tend to excessively reduce the diameter of the wheel 5. As it is, with a double dressing and truing operation, "bell-mouthing" of the workpiece is practically eliminated, and the finished piece has a very smooth internal surface.

As we believe ourselves to be the first to provide means for automatically dressing a grinding wheel at a plurality of stages in the course of the reduction of a workpiece, 35 we wish to claim the same broadly, however carried out, and we note in this connection that while the invention is described as applied in connection with the work caliper mechanism invented by Heald, Guild, Burns and Garno and described in their said application Serial No. 4,466, it could equally well be used in connection with the invention of one of us, viz, Guild, as shown in application Serial No. 48,734, wherein is shown mechanism to automatically inaugurate the dressing and truing of the wheel in response to movement of the feed screw 11, (present drawings), with means for compensating for the wear on the grinding wheel.

45 In the subjoined claims, the words "reciprocate", "reciprocation", and "traverse" are to be taken to mean to and fro movement and not to include a movement to a position followed by a cessation of movement.

50 We claim,

1. In an internal grinding machine, the combination with a grinding wheel, work holding means, and means for reciprocating one of said parts relative to the other, of a 55 wheel dressing device, and automatic means

for extending the amplitude of said reciprocation a plurality of times during the operation on a single work-piece, whereby to dress said wheel a plurality of times during said operation.

2. In an internal grinding machine, the combination with a grinding wheel, a work holding device, and means for reciprocating one of said parts relative to the other, of a wheel dressing device having a single operative position in the path of said grinding wheel, and automatic means for extending the amplitude of said reciprocation a plurality of times during the operation on a single workpiece, whereby to dress said wheel 70 a plurality of times during said operation.

3. A grinding machine comprising, in combination, a grinder, a work holder, a support and a truing tool mounted on said support, means for causing relative traverse between the grinder and said work holder, means permitting the extending of said traverse to include the support and the truing tool in the range of relative travel of said grinder, thus providing two ranges of relative travel, automatic means for shifting from the shorter range to the longer range and back again a plurality of times during the grinding of a single workpiece but causing resumption of the longer range when the sizing mechanism 90 has reached another predetermined position, the aforesaid means that causes resumption of the shorter range again causing such resumption after the second alteration to the longer range.

4. A grinding machine comprising, in combination, a grinder, a support, a work holder and a truing tool mounted on said support, means for causing relative traverse between the grinder and said support, including means permitting altering the extent of said traverse between two ranges, one of which carries the parts through operative traverse between the grinder and work holder alone, and the other of which carries the parts through operative traverse between the grinder and both the work holder and truing tool, a work sizing mechanism, means brought into action when said work sizing mechanism reaches a predetermined position 105 for altering the said traverse from the shorter to the longer range, means automatically causing resumption of said shorter range, means preventing immediate subsequent resumption of the longer range despite the maintenance of said sizing mechanism at said predetermined position, and means to again extend the traverse to the longer range when said work sizing mechanism reaches the second predetermined position.

5. In a grinding machine, a grinding wheel, a wheel dressing device normally out of the path of said grinding wheel, a work sizing mechanism, means responsive to movement of said sizing mechanism for bringing 120

said dressing device into the path of said wheel, said dressing device occupying a given point, and means for causing said wheel to be dressed at a plurality of different stages in the reduction of said workpiece by relative reciprocation between said wheel and said dressing device, said dressing device being at such times at said given point.

6. In a grinding machine, a grinding wheel having a reciprocatory working traverse relative to the work, a truing tool, a work sizing mechanism, means set in operation by said sizing mechanism for automatically increasing the traverse of said wheel to dress it with said truing tool when the work reaches a first predetermined size, means brought about by said increased traverse for resuming normal traverse between said work and wheel, and means for again automatically increasing the traverse of said wheel to dress it with said truing tool upon said work reaching a subsequent predetermined size.

7. In a grinding machine, a grinding wheel having a reciprocatory working traverse relative to the work, means operable at a plurality of intermediate points in the grinding of each workpiece for amplifying said traverse to carry said wheel through a wheel dressing position, a grinding wheel dresser for operating on said wheel in its passage through said dressing position, and automatic means for avoiding the dressing of said wheel thereby on its final passage through the dressing position at the conclusion of the grinding of the same workpiece.

8. In a grinding machine, a grinder, a wheel dressing device normally out of the path of said grinder, a work sizing mechanism, and means automatically set in operation by said sizing mechanism for disposing said dressing device in the path of said wheel a plurality of times during the operation on a single workpiece.

9. In a grinding machine, a grinding wheel, wheel dressing mechanism comprising a pivotally mounted diamond, and electromagnetic inaugurated means for moving said diamond into the path of said wheel a plurality of times during the grinding operation on a single workpiece.

10. In a grinding machine, a grinding wheel, an electrical switch mechanism adapted to control a primary wheel dressing operation and a secondary wheel dressing operation, a reciprocating table, and means actu-

ated thereby for progressively moving said switch.

11. In a grinding machine, the combination with a grinding wheel, work holding means, and means for reciprocating one of said parts relative to the other, of a dressing device, means for causing said dressing device to be interposed for a dressing operation in the relative path of travel of said grinding wheel a determinate number of times during the grinding of a single workpiece, and means for insuring one or more relative reciprocations with the said dressing device out of operative position with respect to the grinding wheel between two or more of said dressing operations.

12. In a grinding machine, the combination with a grinding wheel, work holding means, and means for reciprocating one of said parts relative to the other, of a dressing device, and means for causing said dressing device to dress and true said grinding wheel a plural but determinate number of times during the grinding operation on a single workpiece, said determinate number of dressings being less in number than the number of reciprocations between the first and the last dressing operation.

13. In a grinding machine, the combination with a grinding wheel, work holding means, means for reciprocating one of said parts relative to the other, and means for giving said parts an intermittent cutting feed one in relation to the other, of a dressing device, and means for causing said dressing device to dress and true said grinding wheel a plural but determinate number of times during a given advance of said intermittent cutting feed, said determinate number of dressings being less in number than the number of separate feed actuations between the first and the last dressing operation.

14. In a grinding machine, the combination with a grinding wheel, work holding means, means for reciprocating one of said parts relative to the other, and means for transversely feeding one of said parts relative to the other, of automatic means for extending the amplitude of said reciprocation a plurality of times during the operation on a single workpiece at different stages of said transverse feed, and dressing means for dressing said wheel at said amplified reciprocations.

WALDO J. GUILD.
LEWIS CLIFFORD KENYON

CERTIFICATE OF CORRECTION.

Patent No. 1,684,486.

Granted September 18, 1928, to

WALDO J. GUILD ET AL.

It is hereby certified that error appears in the printed specification of the above numbered patent requiring correction as follows: Page 2, line 111, for the word "manipulated" read "multiplied"; page 7, line 90, claim 3, after the word "travel" insert the word "and"; same claim line 94, beginning with the word "but" strike out all to and including the word "range" in line 100; same page, line 110, claim 4, strike out the word "and" and insert the same before the word "means" line 119; same claim, line 122, strike out the comma and words "and means to again extend the traverse to the longer range when said work sizing mechanism reaches the second predetermined position", and insert instead "but causing resumption of the longer range when the sizing mechanism has reached another predetermined position. the aforesaid means that causes resumption of the shorter range again causing such resumption after the second alteration to the longer range"; page 8, line 106, claim 14, for the misspelled word "trans-verse" read "transverse" and that the said Letters Patent should be read with these corrections therein that the same may conform to the record of the case in the Patent Office.

Signed and sealed this 20th day of November, A. D. 1928.

(Seal)

M. J. Moore,
Acting Commissioner of Patents.
